ADJUSTABLE FEED FOR TOOLS

Douglas T. Peden, Ann Arbor, Mich., assignor to
Micromatic Hone Corporation, Detroit, Mich.,
a corporation of Michigan

Application November 13, 1940, Serial No. 365,526

18 Claims. (Cl. 51—184.3)

This invention relates to honing machines, and particularly to a honing machine of new and novel construction which machines a workpiece to accurate dimension while compensating for the stone wear which occurs during the machining operation.

The machine embodies operating principles set forth in the William E. Harris application, Serial No. 116,774, filed December 19, 1936, which matured as Patent No. 2,252,176, on August 12, 1941, and in the application of John E. Kline et al., Serial No. 274,890, filed May 22, 1939. The operating mechanism as set forth in the above-mentioned Kline et al. application comprises a tool carried by a spindle which is expanded by the action of a piston under the influence of fluid supplied to the end of an encompassing cylinder. The opposite end of the spindle from that supporting the tool is provided with a driving and adjusting shaft by which the degree of reciprocation of the tool may be regulated. An adjustable swash plate is employed for producing the reciprocation of the spindle at a predetermined speed relative to the rotation, which relationship may be varied. A unique mechanism is provided for expanding and contracting the abrasive stones of the tools independent of the movement of the piston. The sleeve for operating the additional expanding mechanism neither reciprocates or rotates and is thereby available to the operator for advancing its position in rotation to feed the abrasive stones radially during the operation of the honing tool. An actuating mechanism is provided for advancing the adjusting sleeve which produces the automatic expansion of the abrasive stones during the machining operation. Adjusting mechanism is employed which, upon returning the stones to initial position, may be set to compensate for the amount of stone wear which occurred during the prior operation so that production honing may be accomplished by the device. That is to say, the device is capable of machining all of a number of workpieces to a desired diameter without requiring adjustment of the tool for each of the workpieces being machined, as has been necessary in the past.

Accordingly, the main objects of my invention are; to provide a honing tool with abrasive stones and mechanism for initially expanding them into engagement with a cylinder wall and with further mechanism for automatically feeding them further toward the wall during the machining operation; to provide a tool with mechanism which expands the cutting elements there-

of into engagement with the cylinder wall with a snap action and which progressively expands the elements at a predetermined rate as the machining operation progresses; to expand the abrasive stones of a honing tool progressively toward a cylinder wall during a honing operation at a predetermined rate and retract the stones a less amount after the operation to compensate for the wear of the stones during 5 the machining operation; to provide a machine which operates a honing tool in reciprocation and rotation with a support for a workpiece which reciprocates the workpiece over the tool which has its stones expanded progressively during the 10 machining operation and retracted thereafter a less amount equal to the loss of stone diameter; and in general, to provide a new and novel device for honing by a continuous method which compensates for stone wear, which is simple in 15 adjustment and positive in operation.

Other objects and features of novelty of my invention will be either specifically pointed out or will become apparent when referring, for a 20 better understanding of my invention, to the following description taken in conjunction with the accompanying drawings, wherein:

Fig. 1 is a sectional view of a machine spindle for reciprocating, rotating, and adjusting a honing tool, which embodies features of my invention;

Fig. 2 is a sectional view of the work holding portion of the machine and the table which reciprocates the work over the honing tool;

Fig. 17 is a schematic diagram of the fluid circuit employed for operating the machine illustrated in the foregoing figures;

Fig. 18 is a broken view of the manifold illustrated in Fig. 17, with the valves shown in starting position; and

Fig. 19 is a view of the structure illustrated in Fig. 18, with the valve shown in position to render the honing machine inoperative.

The mechanism for driving the tool in rotation and reciprocation is substantially the same as that illustrated and described in the above-mentioned Kline et al. application. The structure embodies a sleeve 15 which forms the outer wall of the spindle and is preferably of cylindrical form. A nose 16 is provided with a central cylindrical aperture 17 and fluid ports 18 and 19. Within the central aperture 17 a sleeve 22 is mounted having apertures 23 and 24 in communication with the fluid ports 18 and 19, respectively. The sleeve is secured to an enlarged end of a shaft 26 by a pin 27 to join the sleeve to the shaft. The enlarged end of the shaft forms a cylinder for a piston 31 which moves within the sleeve 22 and is provided with a reduced end portion 32 to have clearance at the inner end of the piston.

A hollow shaft 34 extends forwardly of the piston operating in a sleeve 35 which is threaded within the end of the sleeve 22. The hollow shaft 35 has a sleeve 41 journaled at 41a and splined thereto at 41b. The shaft has a pulley 42 secured in driving relation. A suitable belt 43 is employed for driving the pulley 42 in rotation. Over the sleeve 41 a sleeve 44 is mounted for rotational movement relative thereto on a bearing 45. The outer surface of the sleeve 44 is supported by roller bearings 46 which are secured to a sleeve 47 attached to the ends of the sleeve 15 by pins 48. On the rear end of the sleeve 44 a pulley 40 is secured in driving relation, being disposed adjacent to the pulley 42 and driven by a belt 43 both of which are driven from a common motor 33. The pulleys 40 and 42, as well as the driving pulleys 40' and 42', may be of different radial dimensions so as to vary the relative speed of operation of the honing tool in rotation and reciprocation.

The sleeve 44 has on its forward end an annular flange 49 provided with a slot 51 in its face for receiving projections 52 on a washer 53 to form a driving connection. The washer 53 has a cylindrical receptacle 54 in which a ball-shaped projection 55 on an inner raceway 56 is mounted for gyrating sliding movement. The outer raceway 57 of the bearing is secured within a cap 58 having a lug 59 which projects through an aperture 61 in a sleeve 62 having

spaced flanges 63. A pin 64 has its flat face 65 extending between the flanges 63 when projected through the aperture of the lug 59 to provide a pivotal driving connection therebetween.

5 A rod 66 extends through the hollow interior of the shaft 26 and has a threaded end 67 in engagement with the thread 68 on the inner wall of the shaft. A slot 69 is provided on the end of the rod 66 in which a split washer 71 is mounted through a slot 72 in the sleeve 62 secured in position by a spring ring 73. The split washer 71 locks the sleeve 72 to the rod 66 for longitudinal movement therewith. The rod 66 is the joining means between the sleeve 62 and 10 the cap 58 and no reciprocation could occur except for this threaded connection. By turning the rod 66 by means of an attached thumb nut 74 the sleeve 62 is moved longitudinally on the shaft 26 to regulate the degree of tilt to the 15 cap 58 on a pair of balls 60 on which the cap is pivoted to thereby regulate the degree of reciprocation of the workpiece, or tool that is supported on the end of the sleeve 38.

The pulley 40 drives the inner races 56 of the 20 bearings while the pulley 42 drives the shaft 26 and, through the balls 60, the cap 58 in rotation. When both the shaft 26 and raceway 56 are rotated at the same speed no reciprocation occurs to the sleeve 22. When one is rotated and the 25 other retained stationary a simple harmonic motion is produced. When the driving speeds are dissimilar the simple harmonic motion becomes a hunting motion which will repeat itself only after operating an appreciable length of 30 time. After the rod 66 has been adjusted to provide the desired degree of oscillation to the sleeve 22 a clamping nut 70 may then be employed to maintain such adjustment.

The nose 16 has an extending sleeve 76 secured by set screws 77. A sleeve 78 is rotatably mounted upon the sleeve 76, retained against longitudinal movement by a plurality of balls 80. A sleeve 81, having an internal thread 82 has an outer raceway portion 83 on its inner end which 40 forms a bearing with an inner raceway portion 84 coupled by balls 85. A slot 86 is provided in the wall of the sleeve 35 through which a pin 87 extends when joining the piston extension 45 to the raceway 84. The movement of the piston moves the rod 34, the pin 87, the raceway 84, and the sleeve 81 to advance or retract the abrasive tool. The movement is limited by the 50 end of the sleeve 35 against which the piston 55 abuts in its forward movement and by the projection 32 during its rearward movement.

Referring more particularly to the enlarged view of Fig. 3, a ring gear 88 of material width is secured on the inner side of the adjusting 60 sleeve 78 by a pin 79 to rotate therewith. A pair of pinion gears 89 are journaled in the outer portion of the sleeve 81 through which the gear teeth project to engage teeth 91 on an outer race 92 which forms a roller bearing with an inner race 93 and spaced rows of balls 94. The teeth 91 of the race 92 are provided with a thread 95 which mate with the thread 82 provided on the inner wall of the sleeve 81. A tool adjusting head 96 is longitudinally movable 65 within the end of the sleeve 35. A pin 98 extends through diametrically disposed slots 97 for connecting the head 96 to the inner race 93 of the sleeve 81. By rotating the sleeve 78, the 70 ring gear 88 rotates therewith to drive the 75

pinion gears 89 which in turn rotates the outer race 92 to move the race longitudinally through the engagement of the threads 95 with the threads 82. The race 92 advances with the race 93 and produces a similar movement to the adjusting head 96.

It will be noted that the ring gear 88 and the pinions 89 are of material width and length respectively, so that an appreciable longitudinal movement may be effected to the head 96 through the movement of the piston 31 and the additional movement produced by the rotation of the sleeve 78. The sleeve 35 has a flanged collar 99 threaded thereon. A driving element 101 is mounted forwardly of the collar 99 supported in position by a flanged sleeve 102. A ball bearing 103 is mounted between the flange and the tool supporting element.

A tool is mounted on the supporting element 101 by a flanged sleeve 106. The tool embodies a tubular body portion 107 having a flanged sleeve 108 thereon in the flange of which a pin 109 projects to extend in an aperture 111 in the tool driving element 101. A pin 112 prevents the relative rotation between the body portion 107 and the sleeve 108. Axially movable within the body portion is a rod 113 having a conical extension 114 on its forward end. A collar 115 is mounted on a stub 116 on the inner end of the rod 113 which is supported by a pin 117 on the projection 118 of the attaching head 119. A ball 121 permits the universal movement of the rod 113 relative to the head 119.

The head 119 fits within a recess 122 provided in the forward end of the adjusting head 96. An annular slot 123 is provided in the periphery of the head 119 for receiving a ball 124 to form a lock therefor. The ball is positioned in a slot 125 in the wall of the head 96 which mates with a recess 127 in the wall of the sleeve 35 at the forward end of the sleeve. When the head 96 is adjusted to its forwardmost position by the piston and the adjusting sleeve 78 the ball enters the slot 127 in the sleeve 35 thereby releasing the ball 124 from its position within the annular slot 123 in the head 119 so that the head 119 is removable from the head 96. It is therefore a simple operation to attach the head of the adjusting device to the adjusting head 96. At the end of the forward movement of the adjusting device the release of the head 119 from the head 96 is automatic. After the head 119 is inserted in the head 96 the operation of the piston, as viewed in Fig. 1, will draw the heads 96 and 119 to the left, moving the ball from the slot 127 to lock the heads together.

As illustrated in Fig. 2 the tapered end portion 114 of the rod 113 engages the inner sloping surfaces of the stone holders 130 on which stones 131 are secured in any suitable manner, well known in the art. Spring fingers 132 are secured in slots in the tool body 107 which extend over the stone holders 130 for urging them radially inwardly. As the rod 113 is moved to the right, as viewed in Fig. 2, the abrasive stones 131 are moved radially outward against the pressure of the springs 132 and when the rod 113 is moved to the left the spring moves the stones toward the axis of the body 107.

The washer 100 is provided with four slots 104 and with four apertures 105. The driving head 101 is provided with a pair of pins 130 which project within a pair of the slots 104 in which rollers 131 are mounted. A similar pair of pins 130 (not illustrated) are supported in the collar 75

99 and project in the additional pair of slots 104 for the purpose of providing driving connection while at the same time permitting the driving head 101 to float within the flanged sleeve 102. A plurality of balls 110 are disposed in the apertures 105 to provide a thrust bearing relation therewith. Since the adjusting rod 115 is mounted for universal movement on the projection 118, the entire tool is free to float relative to the workpiece so that the tool and workpiece need not be accurately aligned.

Now referring to Figs. 8 to 16, inclusive, I have illustrated a structure which cooperates with the adjusting sleeve 78 and the other mechanism associated therewith for providing automatic advancement of the sleeve and therefore of the abrasive stones during the honing operation. This control structure embodies operating parts which compensate for the stone wear after each honing operation so that at the beginning of each operation on a workpiece the abrasive stones are contracted to substantially the same diameters. It was found that there is a definite relation between the hardness of the workpiece and the type of abrasive material by which the amount of erosion of the stones can be accurately assumed and compensated for at the end of each operation. For example, on a hard steel with a soft stone to remove approximately $\frac{1}{1000}$ of material in a $\frac{1}{4}$ inch hole substantially $\frac{1}{1000}$ of the stone diameters will be removed. As a result, when a plurality of successive workpieces are being machined, the adjusting mechanism may be set to allow for a $\frac{1}{1000}$ change in diameter of the tool for each operation. The degree of expansion of the tool during the operation being fixed, all of the workpieces being machined should be finished to a desired diameter within fractions of a tenth of a thousandth of an inch.

The sleeve 78 is provided with a pair of ratchet wheels 133 and 134 having teeth of opposite hand aligned thereon. That is to say, the teeth on the wheel 133 are disposed to turn the wheel in a counter-clockwise direction while the teeth on the wheel 134 are disposed to turn the sleeve 78 in a clockwise direction. A housing 135 for supporting the sleeve 15 of the device contains a cylindrical aperture 136. A cylinder 137 is mounted within the aperture 136 to be moved longitudinally on a stationary hollow piston rod 138. Suitable packing material 139 seals the end of the cylinder on the rod. Similarly, on the rod a piston 141 is secured while passageways 142 and 143, respectively, are provided through the rod 138, terminated at the right and left hand side of the piston, respectively. Caps 144 in the end of the cylindrical aperture 136 form a support for the piston rod 138 and a passageway for the fluid to the apertures 142 and 143. The aperture 142 communicates through a control valve 146, for regulating the flow of fluid from the passageway. When fluid is introduced to the passageway 142 it is passed around the valve 146 through a passageway 147 closed by a ball check valve 148 when the flow of fluid is in the opposite direction.

The lower face of the cylinder 137 is provided with a plurality of teeth 149 forming a rack which is in mesh with a pinion 151. The pinion is mounted on a shaft 152 which is suitably bearinged within the housing 135 on the forward end of which a pinion 153 is mounted. The pinion is disposed in mesh with a ring gear 154 which is mounted for rotational movement on the sleeve

15. A sleeve 155 encompasses the ring gear 154 and the cylindrical extension thereof. A slot 156 in the ring gear 154 has a ratchet finger 157 pivoted therein urged by a spring 158 into engagement with the teeth of the ratchet wheel 133. A similar slot 159 in the ring gear 154 contains a ratchet finger 161 for engagement with the teeth of ratchet wheel 132 urged into engagement by a spring 162. A cam element 163 operates in a slot 164 in the sleeve 155 for the purpose of engaging a projecting end 166 on the ratchet finger 157. A finger 168 provides a visible indication of the cam element relative to a scale 169 provided on the face of the sleeve 155. The cam is maintained in position by a thumb screw 171.

16. A plunger 172 is supported in the flange of the sleeve 155 in position to engage the extension 173 of the cam finger 161 when the ring gear is in initial operation position, that illustrated in Fig. 8. The plunger may be moved inwardly to disengage the teeth on the ratchet wheel 134 so that the ratchet wheel may be rotated by hand. A stop block 174 is mounted on the ring gear, having an indicating finger 175 thereon. An adjustable stop block 176 is mounted in a slot 177 in the sleeve 155, retained in adjusted position by a thumb screw 178. An indicating finger 179 locates the position of the block relative to a scale 181 mounted on the flange 155.

17. In Fig. 9, I have illustrated the housing 135 as being provided with a cylindrical aperture 182 having a spool 183 rotatable therein. The spool is rotated by a stem 184 from an adjusting knob 185 containing a scale 186 which is attached to the rod 184 by the spool for accurately positioning the spool in accordance with the scale on the knob. Fluid is introduced through the aperture 182 into the passageway 143 where it operates on the left hand end of the cylinder 137 to move the cylinder to the left, as viewed in the figure. The fluid in the right hand end of the cylinder 135 must be forced through the passageway 142 and through the valve 146 to the tank.

18. The valve is provided with a V-shaped notch 187 by which the fluid from the passageways 142 and 145 is metered. A block 188 closes the aperture 189 so that the fluid entering the notch 187 will pass through a slot 191 into the tank through aperture 192 by a suitable conduit attached thereto. After the cylinder 137 has moved to the left the fluid is reversed in the passageways 190 and 192 and the pressure entering the latter passageway will be by-passed by the ball check valve 148 into the passageways 145 and 142 to move the cylinder 137 to the right, to the position illustrated.

19. The fluid on the opposite end of the cylinder will flow from the passageway 143 and 190 without restriction so that a rapid return movement of the cylinder is thereby obtained. Annular grooves 194 and 195 are provided at each end of the spool 183 interconnected by a passageway 196 which is connected to a drain tank through a passageway 197. Any fluid which may leak along the spool will be returned to drain in this manner and will prevent the valve from leaking.

20. In operating the device, a workpiece 198 is mounted in a universal support 199 retained in position by suitable means as by a thumb nut 200. The support is mounted on a base 201 which is attached to a reciprocating carriage 202. The work is mounted in this manner to have uni-

versal movement so that its surface will align with those of the tool. Any misalignment is compensated for by the tool which may shift to have its axis conform to the axis of the workpiece. A hopper feed is preferably employed for the work so that the machine will be entirely automatic.

21. After a workpiece has been clamped into the machine the table 202 moves the workpiece over the stones 131 of the tool. Thereafter the rod 113 is moved by the piston 31 to produce the radial movement of the stones 131 into contact with the surface of the workpiece. At the same time the motor 33 is energized to drive the tool in reciprocation and rotation while the table 202 continues to stroke the workpiece over the stones. The table movement superimposes a slow feed movement in reciprocation onto the rapid reciprocation produced by the drive mechanism. When the structure, as illustrated in Fig. 1, is employed, the operator periodically grasps the sleeve 78 and rotates it clockwise to advance the abrasive stones toward the wall being machined until a desired diameter is reached.

22. When the construction illustrated in Fig. 8 is employed, the stop block 178 and the cam block 163 is first set so as to regulate the degree of advancement of the sleeve 78 as well as its amount of retroactive movement. Fluid is introduced into the opening 198 to move the cylinder 137 to the left under control of the fluid in the right hand end of the cylinder which is metered through the valve 136. This movement rotates the pinions 151 and 153 which in turn rotate the ring gear 154 to rotate the sleeve 178 by the connection of the pawl 161 with the ratchet wheel 134. The ratchet wheel 133 and pawl 157 being carried along therewith.

23. Before the end of this advance movement, the pawl 157 engages the end of the cam 163 which releases the pawl from the ratchet wheel 133, both of which continue to advance in the same predetermined relation to each other. This occurs because the pawl 157 is carried by the ring gear 154 and the ratchet wheel 133 is attached to the sleeve 78 which is advanced by the ratchet wheel 134. The advancement of the stones continue until the stop block 174 engages the block 176 and thereafter machining is continued for a short time without further advancement of the stones to complete the finishing operation.

24. Thereafter the fluid is reversed to retract the piston 31 which retracts the rod 113 and permits the stones 131 to contract. The reversal of fluid also interrupts the stroking movement of the table 202 which is returned to its initial position with the work moved away from the tool. The reversal of the flow of fluid moves the cylinder 137 to the right and rotates the ring gear 154 counterclockwise. During the initial movement of the ring gear, the pawl 157 will be held out of contact with the teeth of the ratchet wheel 133 by the cam 163 and no movement will occur to the sleeve 178. After a predetermined degree of return movement, regulated by the position of the cam 163, the projecting end 166 of the pawl 157 moves out of contact with the cam 163 and the pawl 157 moves into engagement with the teeth of the ratchet wheel 133 and returns the ratchet wheel and sleeve 178 to a new initial position. It will be noted that the sleeve 178 is moved clockwise a greater amount than in the counterclockwise direction, the difference in movements adjusting the stone diameter con-

forming to the amount of wear which has occurred to the abrasive stones. The setting to compensate for the amount of wear may be obtained empirically and the degree of advancement of the abrasive stones during the honing operation to machine to a desired diameter is selected in a like manner.

The tool begins each operation with the stones set at a desired diameter and after being moved to engage the surface of the bore by the movement of the piston 31 is thereafter advanced a predetermined amount to machine the bore to a desired diameter. After each operation the expanding mechanism is retracted a less amount to compensate for stone wear so that the tool will have the same diameter that it had at the beginning of the operation.

Referring to Figs. 17, 18 and 19 I have illustrated diagrammatically the fluid circuit employed to produce the automatic operation of the machine to have it perform the complete cycle to move the workpiece over the honing tool, to expand the abrasive stones of the tool, to drive the tool in rotation and reciprocation, to expand the abrasive stones during the honing operation, to stroke the workpiece over the tool, to continue the machining operation after the expansion of the abrasive stones, and to collapse the abrasive stones and move the workpiece out of engagement with the tool.

A pair of pumps, 205 and 206, are driven from a shaft 207 and supply fluid to the manifold 212. A pressure relief valve 203 is connected in the circuit of the pump 205 while a relief valve 210 is connected to the pump 206, the latter valve having an operating knob 211 by which it may be readily adjustable. The manifold 212 controls the flow of fluid through the various circuits to the cylinders 137, 208 and that containing piston 31, the cylinder 208 being employed to reciprocate the table 202. Fluid from the various cylinders, relief valves and manifold is returned to a tank 213 from which it is circulated by the pumps. An operating handle 214 is employed to initiate the cycle of operation while a handle 215 returns all of the fluid under pressure to the tank so that the operation may be interrupted at any point in its cycle.

When the table 202 is moved to the right the valve body 226 is positioned at the left in view of the fact that the dog 227 is in the dot and dash line position 228. Fluid from the port A passes through the circuit 229, through the circuit 231, through circuit 232, through the ball-check 233 to the righthand end of the cylinder 234 for moving the valve body 235 to the right. Fluid from the port A then flows into the port E, while fluid from the port F passes from the circuit 236 through the valve body 237 and to tank. This produces the high speed operation of the table 202 to the left. This movement rocks the dog 227 to the dash line position illustrated in Fig. 18 to move the valve body 226 to the right. Pressure from the port A passes through the circuit 229 through the circuits 239 and 241, through the ball-check valve 242 into the opposite end of the cylinder 234 to operate the valve body 235 to the right, the position illustrated in the figure. This reverses the flow of fluid from port A to port E, to port F which reverses the movement of the piston in the cylinder 208 and moves the table 202 to the right. Fluid from the circuit 229 also passes through the circuit 243 to the righthand end of the valve body 75

237 to move the body to the left, as illustrated in the figure. This produces a flow of fluid from the pressure line C to the line D which operates the piston 31 in the cylinder 15 for producing the initial expansion of the honing stones within the bore of the workpiece. Pressure also passes through the circuit 244 into the upper end of the cylinder 245 for moving the timing valve 246 downwardly therein. A time control of the movement of the valve 246 is effected by the control of the flow of fluid from below the piston by the flow control valve 241. As the table 202 moves to the right the dog 227 will be operated to the position 228 to move the valve body 238 to the left, which will shift the valve body 235 to reverse the flow of fluid in the cylinder 208 to reverse the operation of the carriage 202. The flow of fluid from the ports E and F to tank when pressure is introduced into the opposite port is cut off from the tank by the valve body 237 and the fluid must therefore flow through one or the other flow control valves 248 to control the movement of the table by controlling the flow of the exhaust fluid on the side of the piston opposite to that into which pressure is being introduced.

Pressure is introduced from the conduit 216 through the conduit 222, as illustrated in Fig. 17, to the piston 137 to produce movement of the cylinder which produces the feed movement of the stones during the honing operation. The table will continue to reciprocate in this manner until the handle 214 is reversely moved manually to the position illustrated in Fig. 19, or until the piston 246 moves to the bottom of its cylinder for permitting the fluid in the circuit 249 to pass through the circuit 251 to operate the valve body 225 to the left. This movement cuts off the flow of fluid through circuit 231 so that when the dog 227 is moved into the position 228 herein illustrated, fluid through the circuit 232 to the end of the cylinder 234 is cut off and the valve body 235 will not be reversed so that the table 202 will continue to travel to the right.

Fluid from the circuit 249 also passes through the circuit 252 to the circuits 253 and 254 to the lefthand end of the valve body 237 for moving it to the right. In this position the fluid to the pistons 31 and 137 is cut off and fluid from the circuit 256 is introduced into the righthand side of the pistons 137 and 31 to produce the contraction of the abrasive stones.

Fluid from the port E now passes through the circuits 257 and 258 to tank. This permits the rapid travel of the table to the right as the workpiece is moved away from the honing tool. Fluid from the circuit 252 passes through the flow control valve 249 by unseating the ball 259 to deliver fluid to the lower side of the piston 256 for immediately returning the piston to the top side of the cylinder. Control valve 261 is employed in the circuit at either end of the cylinder 254 for controlling the movement of the valve body 235 to thereby regulate the dwell time of the table 202 at each end of its cycle of reciprocation. When pressure in the circuit 216 is reduced the switch 218 operates to interrupt the operation of the motor and all the parts are returned to their initial position and their operation interrupted.

It has been pointed out hereinabove that the return movement of the cylinder 137 operates the sleeve 178 in reverse movement a portion only of its advance movement to compensate for the stone wear which occurred during the machining operation. The diameter of the stones at the end of the operation will be the same as the di-

ameters before the operation so that like operations will be produced by the tool on similar workpieces. In commercial production, a plurality of workpieces may be finished to ten thousandths of an inch accuracy without requiring skilled labor or the degree of time heretofore thought necessary.

While a single embodiment of the invention has been described and illustrated, it will be apparent to those skilled in the art that various changes, omissions, additions and substitutions may be made therein without departing from the spirit and scope of the invention, as set forth in the accompanying claims.

What is claimed is:

1. In a honing device, a tool, a plurality of radially adjustable honing stones on said tool, cam means for moving said stones radially, means for moving said tool in reciprocation and rotation, fluid means for moving said cam means while said tool is operating, a rotatable sleeve through which said tool is operated, and mechanical means between said fluid and cam means operated by the movement in rotation of said sleeve for additionally moving said cam means while the tool is operating.

2. In a honing device, a honing tool, abrasive stones on said tool, a longitudinally movable cam for radially moving said stones, a rotatable sleeve which is normally stationary from which said tool projects, and mechanism interconnecting said sleeve and cam for moving said cam when said sleeve is rotated.

3. In a honing device, a honing tool, abrasive stones on said tool, a longitudinally movable cam for radially moving said stones, a rotatable sleeve from which said tool projects, an internal gear secured to said sleeve, a second rotatable sleeve disposed within said first sleeve and retained against axial movement relative to said cam and having an internal thread, a gear having threads on the top face of the teeth engaging the thread of said second rotatable sleeve, and gears carried by said second rotatable sleeve joining the teeth of said threaded gear with those of the internal gear.

4. In a honing device, a honing tool, abrasive stones on said tool, a longitudinally movable cam for radially moving said stones, a rotatable sleeve from which said tool projects, an internal gear secured to said sleeve, a second rotatable sleeve disposed within said first sleeve and retained against axial movement relative to said cam and having an internal thread, a gear having threads on the top face of the teeth engaging the thread of said second rotatable sleeve, gears carried by said second rotatable sleeve joining the teeth of said threaded gear with those of the internal gear, and means joining the threaded gear to the cam.

5. In a honing device, a honing tool, abrasive stones on said tool, a longitudinally movable cam for radially moving said stones, a rotatable sleeve from which said tool projects, an internal gear secured to said sleeve, a second rotatable sleeve disposed within said first sleeve and having an internal thread, a gear having threads on the top face of the teeth engaging the thread of said second rotatable sleeve, gears carried by said second rotatable sleeve joining the teeth of said threaded gear with those of the internal gear, an inner race, balls joining the inner race to the inner surface of said threaded gear forming a thrust bearing relation therebetween, a rotatable

sleeve in said inner race having a slot, a cam supporting head in said last sleeve, and a pin extending through said slot and joining said inner race with said cam supporting head.

6. In a honing device, a honing tool, abrasive stones on said tool, a longitudinally movable cam for radially moving said stones, a rotatable sleeve from which said tool projects, an internal gear secured to said sleeve, a second rotatable sleeve disposed within said first sleeve and having an internal thread, a gear having threads on the top face of the teeth engaging the thread of said second rotatable sleeve, gears carried by said second rotatable sleeve joining the teeth of said threaded gear with those of the internal gear, an inner race, balls joining the inner race to the inner surface of said threaded gear forming a thrust bearing relation therebetween, a rotatable sleeve in said inner race having a slot, a cam supporting head in said last sleeve, and a pin extending through said slot and joining said inner race with said cam supporting head.

10 7. A thrust bearing having an inner and outer race, and gear teeth on the periphery of the outer race thereof.

8. A thrust bearing having an inner and outer race, gear teeth on the periphery of the outer race thereof, and threads on the outer ends of the gear teeth.

30 9. A threaded cylinder, teeth cut normal to said threads forming a gear with thread portions on the ends thereof.

35 10. A threaded cylinder, teeth cut normal to said threads forming a gear, a bearing race adjacent the inner wall of said cylinder, and anti-friction elements joining said bearing race to said cylinder in bearing relation.

11. In a honing device, a rotatable sleeve having an internal thread and slots in its wall, a piston for positioning said sleeve longitudinally, a threaded cylinder having longitudinally disposed teeth threaded in said sleeve, a bearing race within said cylinder, anti-friction elements joining said race to said cylinder, an internal gear surrounding said sleeve, and gears carried in the slots in said first sleeve, the teeth of which project therefrom into engagement with the teeth of the cylinder and those of the internal gear.

45 12. In a honing device, a rotatable sleeve having an internal thread and slots in its wall, a piston for positioning said sleeve longitudinally, a threaded cylinder having longitudinally disposed teeth threaded in said sleeve, a bearing race within said cylinder, anti-friction elements joining said race to said cylinder, an internal gear surrounding said sleeve, gears carried by said sleeve and extending through the slots therein into engagement with the teeth of the cylinder and those of the internal gear, a sleeve having a slot in its wall disposed within said bearing race, a tool carried by said sleeve, and a cam receiving head within said sleeve joined through said slot to said bearing race.

50 13. A rotatable and reciprocable sleeve, a longitudinally movable supporting head having a ball receiving aperture, a ball receiving slot at the end of said sleeve, a tool, an adjustable cam in said tool having a head insertable in said supporting head, said cam head having an annular slot in which the ball is insertable for locking said heads together when moved away from said slot in the sleeve.

14. In a honing device, an abrading tool, abrasive elements carried by said tool for radial movement, a cam for producing radial movement of said elements, fluid means for operating said cam, mechanical means between said fluid means and cam for further moving said cam during each honing operation, and means for retracting said cam a predetermined lesser amount than said advancement to compensate for wear of the abrasive elements.

15. The method of honing which includes, the rapid advancement of the honing stones of the tool to a predetermined diameter, the slow feeding of the stones during the honing operation, and the retraction of the stones after the operation an adjustably lesser amount than said advancement to compensate for stone wear occurring during each honing operation.

16. The method of honing which includes the steps of reciprocating and rotating a honing tool, of stroking a workpiece in reciprocation over said tool, and of rapidly expanding the stones of the tool to honing position, of further advancing the

stones during the honing operation to a desired diameter and of retracting the stones a less amount than the expansion to the original stone diameter.

17. The method of honing which includes the steps of reciprocating and rotating a honing tool, of stroking a workpiece in reciprocation over said tool, and of rapidly expanding the stones of the tool to honing position, of further advancing the stones during the honing operation to a desired diameter, and of retracting the stones, upon the conclusion of said operation, an amount equal to the total of said expansion and advancement less the amount of wear occurring on said stones during said operation.

18. The method of honing which includes the automatic compensation for wear occurring on abrasives, as a result of their operation on a workpiece, during the retracting phase of each honing operation by returning the hone to the diameter which it had before the wear occurred.

DOUGLAS T. PEDEN.
